(57) **CLAIM**

The ornamental design for a food packaging for frozen or shelf-stable foods, as shown.

DESCRIPTION

FIG. 1 is a perspective view of a first embodiment of a food packaging for frozen or shelf-stable foods showing my new design.

FIG. 2 is a top plan view of the first embodiment of the food packaging for frozen or shelf-stable foods of FIG. 1.

FIG. 3 is a bottom plan view of the first embodiment of the food packaging for frozen or shelf-stable foods of FIG. 1.

FIG. 4 is a left elevation view of the first embodiment of the food packaging for frozen or shelf-stable foods of FIG. 1.

FIG. 5 is a right elevation view of the first embodiment of the food packaging for frozen or shelf-stable foods of FIG. 1.

FIG. 6 is a front elevation view of the first embodiment of the food packaging for frozen or shelf-stable foods of FIG. 1; and,

FIG. 7 is a back elevation view of the first embodiment of the food packaging for frozen or shelf-stable foods of FIG. 1.

In the drawings, the broken lines depict unclaimed subject matter only and form no part of the claimed design. The parallel wavy lines are shown to indicate no particular depth.
